CLAIM

The ornamental design for a food container, as shown and described.

DESCRIPTION

FIG. 1 is a top perspective view of a food container, the cover portion removed for clarity of illustration.

FIG. 2 is a bottom perspective view thereof.

FIG. 3 is a top plan view thereof.

FIG. 4 is a bottom plan view thereof.

FIG. 5 is a left side elevational view thereof, the base portion being symmetrical such that a right side elevational view thereof, a front view thereof, and a rear view thereof are each identical to the left side elevational view thereof.

FIG. 6 is a top perspective view of the food container, the base portion removed for clarity of illustration.

FIG. 7 is a bottom perspective view thereof.

FIG. 8 is a top plan view thereof.

FIG. 9 is a bottom plan view thereof.

FIG. 10 is a left side elevational view thereof, the cover portion being symmetrical such that a right side elevational view thereof, a front view thereof, and a rear view thereof are each identical to the left side elevational view thereof.

FIG. 11 is a top perspective view of the food container.

FIG. 12 is a bottom perspective view thereof.

FIG. 13 is a top plan view thereof.

FIG. 14 is a bottom plan view thereof; and,

FIG. 15 is a left side elevational view thereof, the food container being symmetrical such that a right side elevational view thereof, a front view thereof, and a rear view thereof are each identical to the left side elevational view thereof.

Stippling and tangency lines in the drawings represent the three-dimensional contours of the design, and are not intended to indicate surface decoration. The broken lines in the drawings are for illustrative purposes only and form no part of the claimed design.
